UNITED STATES PATENT OFFICE.

ALFRED PAGE AND SAMUEL S. BLOOM, OF PHILADELPHIA, PENNSYLVANIA.

ARTIFICIAL TOOTH.

SPECIFICATION forming part of Letters Patent No. 445,281, dated January 27, 1891.

Original application filed February 6, 1890, Serial No. 339,405. Divided and this application filed June 25, 1890. Serial No. 356,740. (No model.)

To all whom it may concern:

Be it known that we, ALFRED PAGE, a citizen of the United States, and SAMUEL S. BLOOM, a subject of the Emperor of Russia, both residing at Philadelphia, in the county of Philadelphia and State of Pennsylvania, have invented certain new and useful Improvements in Artificial Teeth; and we do declare the following to be a full, clear, and exact description of the invention, such as will enable others skilled in the art to which it appertains to make and use the same, reference being had to the accompanying drawings, and to the letters of reference marked thereon, which form a part of this specification.

Our invention relates to artificial teeth, and has for its object the provision of economical and reliable means for uniting the teeth to the plate.

The invention consists, essentially, in securing across an opening or bore in the teeth one or more platina strips, to which, after the teeth are baked, a metallic pin is secured by means of a suitable solder or cement. This pin is provided with a head and is made to project beyond the inner side of the teeth to engage the vulcanite or other plate, and thus render the union between the teeth and the plate reliable and secure.

The present invention is a division of an application in the same line of invention filed by us on February 6, 1890, Serial No. 339,405, and the illustration of this present application shown also in the aforesaid application.

The accompanying drawings illustrate the invention.

Figure 1 is a side elevation of a group of teeth, showing the opening with the cross-strips of platina. Fig. 2 is a section of Fig. 1 on line *x* *x*. Figs. 3 and 4 are detached views of the pins.

Similar letters of reference indicate corresponding parts in all the figures where they occur.

A is a group of teeth and the gum of porcelain or other similar material baked or annealed in the usual way.

In the wire or ridge on the inner side we provide openings *aa*, of a suitable depth and

size to receive one or more transverse platina strips *b* and pins *c* engaged therewith. When the teeth are being formed, the platina strip or strips *b* are placed across the openings *aa*, and when the teeth are baked the strip or strips will be secured in place.

In our former application, above referred to, we claimed a pin having a head which was to be inserted till it reached back of the strip or strips and was then turned to give it a secure hold. In the present application we use a double, pronged, or split pin, which is made to clamp upon one or both of the strips, and with this form of pin it is preferable to employ only one strip, although two can be used.

In the drawings, *C* is the pin having the slit or bifurcated stem *c*, which is intended to straddle and clamp upon the strip *b*, as shown in Fig. 2. The pin may be and preferably is made of a single piece of strap metal bent to form the head *C* and the two parts of the stem *C'*. This will give a springy or clamping effect to the stem. We may also make a recess *c'* in one of the sides of the stem, in which the strip is to lie and give a more secure hold. The head *C* projects out from the side, as shown in Fig. 2, to be embedded in the plastic material of the plate and make the union between the plate and the teeth secure.

Having thus described our invention, what we claim, and desire to secure by Letters Patent, is—

1. The combination, in an artificial tooth having an opening in the side, of a strip set across said opening, and a pin having a bifurcated stem clamped upon the strip, as set forth.

2. The combination, in an artificial tooth having an opening, as described, of a strip set across said opening, and a bifurcated pin having a recess in one limb for receiving the strip, as set forth.

In testimony whereof we affix our signatures in presence of witnesses.

ALFRED PAGE.
SAMUEL S. BLOOM.
